UNITED STATES PATENT OFFICE

FRANK K. GARDNER, OF NEW YORK, N. Y., ASSIGNOR, BY MESNE ASSIGNMENTS, TO CORNSTALK PRODUCTS COMPANY, INC., OF NEW YORK, N. Y., A CORPORATION OF DELAWARE

COTTONSEED HULL AND FIBER SEPARATOR

Application filed July 17, 1928. Serial No. 293,466.

This invention relates to devices designed to separate the linters from the waste hulls of cotton seeds.

In the treatment of cotton seeds, the long fibers are easily removed, but a considerable and valuable quantity of the cotton fibers cling to the waste hull or husk, these clinging fibers being commonly called linters.

It is an object of this invention to provide a device for separating the linters from the waste hulls, and to attain the desired result, advantage is taken of the difference in the specific gravities of the hulls and the linters.

In order to obtain a separation, the waste hulls must be thoroughly cooked and treated so as to loosen the cotton fibers from the hulls. When this has been done the liquid mass is highly diluted with water, and agitated to cause the heavier hulls to drop to the bottom and allow the light fibers to float on the water, care being taken to provide sufficient water, as otherwise the linters will be carried down with the hulls.

The above and other objects are attained by the novel construction, combination and arrangement of parts hereinafter described, and shown in the accompanying drawings, constituting a material part of this disclosure, and in which:—

30 Figure 1 is a plan view of the separating system.

Figure 2 is a side elevational view of the same.

Figure 3 is a side elevational view of the system, partly in section.

Figure 4 is a cross-sectional view taken on the broken line in Fig. 3, and shows the left hand portion of the apparatus in sectional elevation.

40 Referring to the drawings, a tank or flow box 5 is divided into a plurality of compartments by the dam boards 6, each of the compartments having inclined bottoms 7 leading toward central discharge openings 8.

45 Supported from the tops of the dam boards and depending into the compartments are perforated metal separator screens 9, the perforations in these screens being of a size sufficient to allow the particles of hull to sift therethrough.

Above the flow box 5, and running longitudinally thereof, is a rockshaft 10, journaled in the bearing 11. Fixed to the rockshaft 10, and extending downwardly into the flowing mass, are a plurality of paddles 12, 55 the lower extremities of the paddles being positioned slightly above the perforated plates 9.

Fixed to the rockshaft is an arm 13, connected to a link 14 which is loosely connected 60 to a crank 15, mounted on a shaft extending from a gear set, as generally shown at 16, which in turn is actuated by an electric motor 17, or any other source of power. With this construction it will be seen that a 65 to and fro oscillative motion is imparted to the paddles to constantly agitate the mass.

Positioned below the flow tank 5 is a hull receiving chamber 18, connected by means of valves 19 to the discharge openings 8. At 70 one end of the hull chamber 18 is a discharge opening 20, controlled by a valve 21, and at the opposite end of the chamber is a water connection 22, and the discharge from the chamber is into a collector box 23. 75

The bottom of a receiving compartment 24 opens at 25 into a pipe which is controlled by a valve 26.

The discharge of the flow box 5 is into the compartment 27, fitted with an inclined screen 80 28, which is removable and divides the compartment laterally. The bottom of the compartment 27 opens at 29 into a flow pipe 30, controlled by a valve 31, and discharges into the receiving tank 32. 85

The receiving tank 32 opens at 33 into a pipe 34 which is connected to a centrifugal pump 35, the latter discharging through pipe 36 into the receiving compartment 24 of the flow box 5. 90

In operation, the flow box 5 is first flooded with water until the water overflows the successive dams 6, and fills each of the compartments. The mass of waste hulls is then pumped into the receiving chamber 24, 95 through the opening 25. The incoming mass of hulls and linters meets the water being discharged from the pipe 36 and is swerved and agitated thereby. The movement of the diluted mass is then across the top of the ad- 100

ja⁵cent dam 6 into the next compartment where the separation of the linters from the hulls begins.

The movement of the mass progressively is from one compartment to the next adjacent compartment, and as it passes through each compartment and over the screen plates 9, it is agitated by the paddles 12, which are constantly rocked by the rockshaft 10.

This action of the paddles 12 prevents settling of the moving fiber with the hulls to the screen plates and causes the hulls to work down through the floating linters and thence through the perforations in the screen plates 9 to the lower divisions of the compartments, where the hulls accumulate around the discharge openings 8.

From time to time the valves 19 are opened to allow the accumulated hulls to discharge into the hull chamber 18, from which the hulls are flushed out by a jet of water entering chamber 18 from water pipe 22, and finally discharged through the opening 20 into the hull receiving chamber 23.

The floating linters ride with the water flow over each successive dam, finally flowing into a chamber 27 on to a screen plate 28. The water passes through fine perforations in screen 28 into the lower half of the chamber 27, and out through an opening 29, and flow pipe 30, into a water chamber 32, from whence it is pumped by a centrifugal pump 35 back into the receiving chamber 24. The cleaned linters accumulate on the fine screen 28 and are removed from time to time.

While the greater portion of the waste hulls will accumulate in the first three or four compartments, it is obvious that this system may comprise any number of compartments, and that both the accumulated linters and the accumulated hulls may be constantly removed by continuous conveyors or by other means. However, it should be noted that the previous manipulation and treatment of the waste hulls and linters, before they are discharged into the separating system, have a great deal to do with the final success of the apparatus and accomplishment of the desired results.

The waste hulls must be thoroughly cooked and treated so as to loosen the cotton fibers from the husk of the cotton seed in order to accomplish satisfactory results.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. An apparatus for separating linters

from waste cotton seed hulls, comprising a flow tank having spaced dam boards to divide the tank into a plurality of compartments, the first compartment having an opening in its bottom through which a mass of linter and hulls to be separated may be introduced, perforated separating plates suspended in each of the compartments except the first and last, paddles positioned in the compartments except the first and last, paddles positioned in the compartments above the separating plates, means for oscillating the paddles to agitate the mass of hulls and linters in a water bath, and apertures in the bottoms of said compartments to enable the precipitated hulls to be drawn off after the linters have been separated therefrom.

2. An apparatus for separating cotton fiber from waste hulls, comprising a flow tank filled with water and divided into a plurality of compartments, perforated separating plates suspended in each compartment except the first and last, means for agitating a mass of fiber and hulls in each compartment through which waste hulls precipitated through the separating plates may be drawn off.

3. An apparatus for separating cotton fibers from waste cotton seed hulls, comprising a flow box filled with water and divided into a plurality of compartments, perforated separating screen plates suspended in each compartment except the first and the last, means for agitating a mass of linters and hulls above the separating plates, means for removing precipitated waste hulls through the plates, and an inclined screen plate in the last compartment upon which the separated cotton fibers may accumulate.

4. In an apparatus for separating cotton fibers from waste cotton seed hulls, a compartment having a perforated screen plate suspended therein, a plurality of paddles positioned in the compartment above the screen plate, means to rock the paddles to and fro, and means in the bottom of the compartment to enable precipitated waste hulls to be drawn off from time to time.

5. In an apparatus for separating cotton fibers from waste cotton seed hulls, a compartment having a perforated screen plate suspended therein, an agitating device positioned in the compartment above the screen plate, and means to enable waste hulls to be drawn off after they have been precipitated through the screen plate.

6. The method of separating cotton fibers from waste cotton seed hulls that have been cooked and treated to loosen the cotton fibers therefrom, which comprises passing a mass of such said hulls and cotton fibers together with a large quantity of water over a plurality of perforated screen plates, agitating the mixture of water, fibers and hulls to precipitate the waste hulls through perforations

in said plates, and then passing the mixture of water and fibers over an inclined perforated screen from which the fibers may be collected after the water has passed through the perforations in the inclined screen.

5 7. The method of separating cotton fibers from waste cotton seed hulls, that have been cooked and treated to loosen the cotton fibers therefrom, which comprises passing a mass 10 together with a large quantity of water over a plurality of perforated screen plates, and agitating the mass and water to cause the waste hulls to be precipitated through the perforations of the screen plates while the 15 free cotton fibers float on the surface of the water.

8. The process of separating fibers from particles of greater specific gravity than the fibers which comprises suspending a mass of 20 mixed fibers and particles in water, passing the suspension over a plurality of perforated screen plates while agitating the suspension sufficiently to maintain the fibers in suspension but insufficiently to keep the heavier particles in suspension whereby said particles will subside through said screen plates, and thereupon passing the remaining suspension of fibers and water over means for effecting a separation of said fibers from said 25 water.

In testimony whereof I have hereunto affixed my signature.

FRANK K. GARDNER.
